UNITED STATES PATENT OFFICE.

ALPHONSE O. PESSOU, OF NEW ORLEANS, LOUISIANA.

CANE-HARVESTER.

SPECIFICATION forming part of Letters Patent No. 769,628, dated September 6, 1904.

Application filed June 23, 1904. Serial No. 213,848. (No model.)

To all whom it may concern:

Be it known that I, ALPHONSE O. PESSOU, a citizen of the United States, residing at New Orleans, in the parish of Orleans and State of Louisiana, have invented new and useful Improvements in Cane-Harvesters, of which the following is a specification.

My invention relates to harvesters of the stalk-cutter type; and it has for its object to provide a simple and light-draft machine adapted to cut sugar-cane close to the ground, thereby saving from one to three joints of the cane, and also adapted to load the cane into carts or deposit the same in windrows.

The invention will be fully understood from the following description and claims, when taken in connection with the accompanying drawings, forming part of this specification, in which—

Figure 1 is a plan view of the machine constituting the present and preferred embodiment of my invention. Fig. 2 is a side elevation of the machine, and Fig. 3 is a detail view illustrating the means for coupling the endless elevator of the machine with the shaft bearing the rear wheels thereof.

Similar letters designate corresponding parts in all of the views of the drawings, referring to which—

A is the main frame of my novel machine. The said frame may be of any construction compatible with the purposes of my invention without involving a departure from the scope thereof, although I prefer to have it comprise horizontal side bars *a*, suitably connected together and provided on their forward portions with inwardly-directed lateral bars *b*, uprights *c*, rising from the connection between the rear portions of the bars *a*, and inclined braces *d*, interposed between and connecting the bars *a* and the upper ends of the said uprights *c*.

B is a transverse shaft journaled in suitable bearings on the rear portion of the main frame and provided with traveling wheels C.

D D are yokes pivotally connected to the forward portions of the frame-bars *a*, so as to swing in horizontal planes, and designed for the connection of mules or other draft-animals.

E E are wheels mounted in the said yokes,

and F F' are upright shafts journaled in vertically-disposed boxes *e*, carried by the forward portion of the main frame and disposed in a transverse plane slightly in rear of the wheels E. The shafts F F' are provided at 55 their lower ends with horizontally-disposed circular knives G, the knife G of the shaft F being lapped with the knife of the shaft F' and arranged immediately under the same for a purpose presently set forth. The shafts F 60 F' are also journaled in boxes *f*, connected by legs *g* to the main frame, and are equipped at their upper ends with cane-knocking reels *h*. The shaft F is further provided, as best shown in Fig. 2, with a loose collar *i*, which 65 is provided with diametrically opposite projections *j* and is interposed between the main frame and a collar *k*, fixed on the shaft F through the medium of a set-screw or other suitable means. The collar *i* is arranged in 70 engagement with the bifurcated arm of a vertically-disposed bell-crank *l*, which bell-crank is connected by a link *m* with a hand-lever *n*, fulcrumed on the main frame and carrying a 75 detent *p*, arranged to engage a segmental rack *q*. In virtue of this construction it will be observed that when the lever *n* is thrown toward the rear the shaft F will be raised, as will also the shaft F', this latter because of the arrangement of the knife of the first-mentioned shaft 80 below that of the shaft F'. It will also be noticed that when the lever *n* is thrown forwardly the shaft F will be positively moved downwardly, while the shaft F' will gravitate until its knife rests upon that of the shaft F. 85 It will further be observed that through the medium of the detent *p* and the segmental rack *q* the knives of the two shafts F F' may be adjustably fixed above the ground at the distance best suited to the condition of the cane 90 to be cut.

H is a transversely-disposed roller journaled in the main frame at a point slightly above the ground.

I is a transverse roller journaled on the 95 main frame at the rear end thereof and disposed in a plane considerably above that of the roller H; J J, idler-rollers mounted on the inclined braces *d* of the main frame, and K a sprocket-wheel mounted on the shaft B and 100

fixed thereto through the medium of a clutch L, as best shown in Fig. 3. The sprocket-wheel K is connected with the roller I through the medium of a sprocket-belt M, a sprocket-wheel N, a spur-gear P, fixed with respect to the wheel N, and a spur-gear Q, fixed with respect to the roller I and intermeshed with the said spur-gear P. From this it follows that when the machine is drawn forwardly and the spur-gear K is fixed on the shaft B the endless elevator R, which takes around the rollers H and I and has its upper stretch arranged on the idler-rollers J, will be driven in the direction indicated by arrow in Fig. 2. It also follows that when the sprocket-wheel K is rendered loose on the shaft B, as when the machine is to be moved over a road from one point to another, the elevator R and the connection between the same and the shaft B will be left idle, so as to render the draft light.

S is a platform disposed at the rear end of the main frame A and inclined transversely and preferably so that its lowermost end is at the right-hand side of the machine. The said platform S is connected at s t to the main frame, preferably in a hinged manner, and is normally supported in the position illustrated by braces u, which are connected to the rear portion of the platform, preferably in a hinged manner, and are provided at their forward ends with depending portions v, let into eyes w on the main frame. By reason of this construction it will be observed that when the braces u are disengaged from the eyes w the platform S may be swung downwardly against the rear end of the main frame, so as to be out of the way, the braces u being interposed between the platform and the rear end of the main frame.

In practice when my novel machine is drawn through a cane-field it will be observed that the knives G will cut the cane-stalks at a point close to the ground, and the reels h, which are rotated by the cane contacting with the perimeters of the knives, will knock the cane back on the elevator R. The said elevator will carry the cane upwardly and rearwardly to the platform S, from whence it will be discharged either into a cart drawn to the side of the machine or into a windrow.

It will be appreciated from the foregoing that my improved machine is adapted to quickly cut and load the cane and at a small cost; also, that the cutting of the cane through the medium of the knives G obviates the necessity of shaving the stubble subsequent to the said cutting. It will further be observed that the cutting of the cane close to the ground materially increases the quantity of saccharine substance afforded by the cane.

I have entered into a detailed description of the construction and relative arrangement of the parts embraced in the present and preferred embodiment of my invention in order

to impart a full, clear, and exact understanding of the same. I do not desire, however, to be understood as confining myself to such specific construction and relative arrangement of parts, as such changes or modifications may be made in practice as fairly fall within the scope of my invention as claimed.

Having described my invention, what I claim, and desire to secure by Letters Patent, is—

1. In a cane-cutter, the combination of a main frame having side bars, rear wheels connected with and supporting the main frame, horizontally-movable yokes pivotally connected to the forward portions of the side bars of the frame, wheels mounted in said yokes, vertically-disposed shafts journaled in the main frame, in rear of the forward wheels, and having horizontally-disposed knives at their lower ends and knocking-reels at their upper ends, a transverse roller mounted in the main frame immediately in rear of the vertical shafts and above the knives thereof, a transverse roller I disposed on the rear portion of the main frame and in a horizontal plane above that of the first-mentioned roller, an endless elevator mounted on said rollers, a driving connection between one of the rear wheels and the roller I for driving the latter by the former, and a laterally-inclined platform arranged to receive cane from the upper portion of the endless elevator.

2. In a cane-cutter, the combination of a main frame, rear and forward wheels supporting said main frame, vertically-disposed shafts arranged side by side and journaled in the forward portion of the main frame and having horizontally-disposed knives at their lower ends and knocking-reels at their upper ends; the knives of said shafts being lapped, a bell-crank engaging the shaft bearing the lowermost knife, a hand-lever fulcrumed on the main frame and connected with the bell-crank, co-acting means on the main frame and the hand-lever for adjustably fixing the latter, a transverse roller H mounted in the main frame immediately in rear of the vertical shafts and above the knives thereof, a transverse roller I disposed on the rear portion of the main frame and in a horizontal plane above that of the roller H, an endless elevator mounted on the rollers H and I, a driving connection between one of the rear wheels and the roller I, and a laterally-inclined platform arranged to receive cane from the upper portion of the endless elevator.

3. In a cane-cutter, the combination of a main frame, wheels supporting the same, an inclined endless elevator mounted in the main frame, cane-cutting means carried by the main frame, means for knocking the cut cane on the endless elevator, a driving connection between one of the wheels and the elevator, a laterally-inclined platform arranged to receive cane from the upper portion of the ele-

vator; said platform being hinged to the main frame so as to swing vertically, and braces pivotally connected to the platform and having depending end portions removably arranged in eyes on the main frame.

4. In a cane-cutter, the combination of a wheel-supported main frame, vertically-movable upright shafts journaled in the main frame and having lapped knives at their lower ends and knocking-reels on their upper ends, a collar loosely mounted on the shaft bearing the lowermost knife, a bell-crank having a bi-

furcated arm straddling and engaging said collar, a hand-lever fulcrumed on the main frame and connected with the other arm of the bell-crank, and coacting means on the frame and lever for adjustably fixing the latter.

In testimony whereof I have hereunto set my hand in presence of two subscribing witnesses.

ALPHONSE O. PESSOU.
